UNITED STATES PATENT OFFICE.

CHARLES C. MILLER, OF FORT WAYNE, INDIANA.

BAG.

No. 924,174.

Specification of Letters Patent.

Patented June 8, 1909.

Application filed November 20, 1908. Serial No. 463,575.

To all whom it may concern:

Be it known that I, CHARLES C. MILLER, a citizen of the United States, residing at Fort Wayne, in the county of Allen and State of Indiana, have invented certain new and useful Improvements in Bags, of which the following is a specification.

This invention relates to bags for retaining and protecting clothing and other articles from dust, moth and other insects and vermin. In bags for this purpose it is essential that the mouth of the bag must be capable of being closed with great tightness in order that there shall be no opening therein through which dust, moths or other insects and vermin may enter into the interior of the bag. It is an advantage if the mouth may be securely but temporarily closed so that the same may be opened without injury to the bag, the articles removed therefrom and the bag capable of subsequent use for the same purpose. It is also an advantage to have the mouth closing means as simple and compact as possible so that the bag may be easily and quickly closed or opened by the user. Another desirable feature is to construct the bag so that the same shall open to considerable extent to enable the user to insert the articles within the bag and have them retained therein with the least crushing of those articles and at the same time expose the bag to the least injury. Another feature in such bags is to have the article supports or hooks which are within the bag so constructed and arranged that they may be removed when not in use, or turned so that there is no possibility of the same puncturing the bag by pressure from the outside when the bag is not in use.

My invention has for its object the construction of a simple and compact bag which shall have embodied in it all the above mentioned features, and it consists in the novel features of construction hereinafter set forth and illustrated in the drawings, in which—

Figure 1 is an elevational view of the upper portion of a bag constructed according to my invention, a portion of the front being broken away to show the interior of the bag; Fig. 2, an exaggerated side view of the bag with the mouth closed; Fig. 3, a side view of the bag in an opened condition; Fig. 3^a a sectional view of a corner of the bag on line 3^a of Fig. 3; Fig. 4, a plan view in perspective, the mouth of the bag being open; Figs. 5 and 6, views of the article banger or hook

support; Fig. 7, a view of the article hanger or hook and Fig. 8, a view of the bag hanger.

Referring to the drawings I form the bag of paper or other moth or vermin proof material of suitable strength, the bag having a front 1, back 2 and sides 3. The sides are folded from top to bottom, as on line 3^a and the bottom is closed by folding or doubling the front, folded sides and back over onto the front or back and sealed tightly thereon, as shown in exaggerated form in Fig. 2.

The front and back sides of the bag are preferably formed of a single sheet of material, the side edges of the sheet being tightly sealed together in any suitable manner. The back 2 is projected above the front 1 to form a flap 4, which is reinforced by a suitable flexible material such as heavy paper 4^a. Fixed to the front of this flap are two or more clasps 5 of well known construction, such as the usual clasp used on arctic shoes and the like; the tongue of each clasp being adapted to be sprung around the edge of the flap and the bag, as described hereinafter.

The outer portion of the back 2 for a short distance below the flap is reinforced at 6 by any suitable material, such as heavy paper; or if the material from which the bag is made is itself of good strength, no reinforcement is necessary. On the outside of back 2 I provide a hanger 7 by which the bag may be hung in a closet or other place. This hanger consists of a plate 8 and a bent rod 9, the inwardly projecting ends of which rod are loosely borne by a raised portion 10 in plate 8. On the inside of back 2 and preferably coincident with plate 8 is plate 11 having formed therein any desirable number of sockets or supports 12 which are adapted to receive the rear portion 13 of hooks or article supports 14. Hook 14 consists preferably of a piece of metal, such as wire, bent so as to adapt the rear depending portion or arm 13 for insertion into sockets 12, the upper portion adjacent to the rear depending portion being curved downward so as to form a shoulder 15 which rests on the top of socket 12. The forward portion 16 of the upper portion is curved upward to form a recess or hollow 17 which is adapted to engage the article which the user desires to place in the bag. The inwardly extending arm 18 passes under and engages the lower end of socket 12 and thus acts as a lock to insure the retention of the hook in the socket. To

place the hook in position it is only necessary to slightly spring either depending arm 13 or arm 18 and slip arm 13 into socket 12. Arm 18 then engages the lower end of 5 socket 12. It will be seen that hook 14 is rotatable about socket 12, so that it can be revolved in either direction until it abuts plate 11. It is thus out of the way and cannot protrude through front 1 when the bag 10 is closed, as for shipment or storage, or display; while, when the hook is in use it can be rotated to any desirable position for supporting the articles within the bag. If a hook is not wanted it can easily be removed 15 from its socket by first disengaging arm 18 from that socket and then withdrawing the hook and its dependent arm 13 from engagement with the socket. Any number of 20 sockets 12 and hooks 14 may be provided for the bag. Plates 8 and 11 are provided with suitable alining openings 19 through which and through back 2 are passed suitable rivets or other means by which the two plates are fixed on the back. Any other convenient 25 manner of mounting the two plates on back 2 will suffice for my purpose.

The folded sides 3 have several advantages. When front 1 is pulled away from back 2, the fold of each side tends to 30 straighten out—that is, line 3^a approaches the plane of the side edges of the front and back, as shown in Figs. 3^a and 4. The lower portion of each side when expanded assumes a position similar to that indicated 35 in Fig. 3^a, the figure being somewhat exaggerated to show thickness of the parts. In this view it will be noticed that the lower portion of the edge (3^a) of the folded side slants upward and outward, while the side 40 in addition takes another fold on approximately line 3^b to accommodate the outward movement of the side. This angularity and additional fold is obvious since the folded side is included with the front and back in 45 the fold of the lower end of the bag which closes the bottom thereof as before described. This capability of expansion of the sides enables the user to open the bag to quite an extent and permits the very 50 easy insertion of the articles into it with comparatively no crushing, and when the bag is closed the folded sides permit of a continuous expansion of those sides so that the articles within the bag are subject to 55 very little crushing, if any at all. It is preferable to mount the article hanger plate far enough below the top of the bag to enable the articles to be hung a suitable dis-

tance beneath the top when closed in order that the articles may be free from crushing 60 from the closing of the mouth of the bag. The expansion of the sides also tends to preserve the bag from damage on being opened, for if the front and back were brought together at the sides the front 65 would be apt to tear away from the back when subjected to the strain of opening. The expansible sides of my bag reduces that likelihood to a minimum because of the wide mouth produced by the expansion of 70 those sides.

To close the bag after the articles are in the same, flap 4 is folded over front 1 and a second forward fold of front 1, back 2 and sides 3 is made approximately on line 75 15, the depth of the second fold depending on the height of the flap above back 2. After the second fold is made the tongues 5^a of clamps 5 are sprung or snapped around the edges of the flap and the adjacent edges of 80 the front 1 and back 2, and the mouth is thereby securely closed.

It is apparent that by my construction I have a bag which is very simple and easy of manipulation, which is capable of being 85 filled and securely closed with safety both to the bag and to its contents, and the article supports or hooks of which are movable or removable at the will of the user for providing additional safety to the bag in shipping or display or use by eliminating the 90 danger of puncture of the bag by the hooks.

What I claim is:

1. A bag comprising a front, a back and two extensible sides, spring clasps on the 95 back adjacent to the side and upper edges thereof, the upper portion of the bag being adapted to be folded forwardly to close the mouth of the bag and the clasps being adapted to be sprung onto the back when 100 the mouth is closed.

2. A bag comprising a front, a back and two folded sides, a flap on the back carrying a spring clasp adjacent to each side edge thereof, the flap and upper portion of 105 the bag being adapted to be folded forwardly to close the mouth of the bag and the clasps being adapted to be sprung around from the front onto the back of the bag when the mouth of the latter is closed. 110

In witness whereof I hereunto subscribe my name this 16th day of November, 1908.

CHARLES C. MILLER.
